CHILD'S TOILET SEAT GUARD

Earle E. Merrett, Ludington, Mich.

Original application July 24, 1936, Serial No. 92,329. Divided and this application August 31, 1937, Serial No. 161,815

4 Claims. (Cl. 4—237)

This invention relates to improvements in child's toilet seats which may be attached to conventional toilet seats.

The present application is a division of the copending application of Earle E. Merrett, Serial No. 92,329, filed July 24, 1936, and particularly relates to a guard attachment in combination with a child's toilet seat.

Objects of the present invention are to provide a sanitary guard or shield attachment for a child's toilet seat which may be conveniently attached to and removed from the seat; to provide a sanitary guard or shield which may be attached to the seat by a simple buttoning operation; and to provide a rugged sanitary guard or shield which is economical to manufacture.

Other objects of the invention will become apparent from the following specification, the drawing relating thereto, and from the claims hereinafter set forth.

20 In the drawing in which like numerals are used to designate like parts in the several views throughout:

Fig. 1 is a fragmentary front elevational view of a child's toilet seat having a guard or shield attached thereto embodying features of the present invention;

Fig. 2 is a fragmentary side elevational view taken substantially along the line 2—2 of Fig. 1 illustrating the toilet seat applied to a conventional toilet seat, which seat is shown in cross section; and

Fig. 3 is an enlarged perspective view of the guard or shield illustrated in Figs. 1 and 2.

Referring to the drawing, a portion of the base 12 of a child's toilet seat is illustrated which is provided with a substantially central opening (not shown) therethrough, and an opening 16 at substantially the center of the front edge and extending from the front edge to the interior central opening. The base 12 of the child's toilet seat is adapted to rest upon a conventional toilet seat 18 as disclosed in the parent application referred to.

45 A cup-shaped sanitary shield 20 which is preferably made of pliable rubber has integral horizontally extending portions 22. The extending portions 22 have downwardly directed openings 24 therethrough which are resilient and which 50 serve to attach the shield to the toilet seat by a simple buttoning operation.

In order to removably mount the guard or shield to the toilet seat 12 with the concave portion of the shield directed inwardly, screws 55 26 having enlarged heads 28 are secured to the

undersurface of the base 12 on opposite sides of the openings 16 with the heads spaced from the underside of the base. The heads are spaced a distance from the under surface of the base substantially equal to the thickness of the horizontally extending portions 22 of the shield.

The shield is mounted to the seat by a simple buttoning operation by passing the horizontal portions 22 over the heads 28 of the screws through the openings 24. The upper surfaces of the horizontally extending portions 22 engage the under surface of the seat when the shield is in its assembled position, and thus assists in steady ing and securing the shield in place.

By making the shield of soft pliable rubber 15 material, danger of injury to the child is lessened; and the shield may be conveniently attached to and removed from the seat by the simple buttoning operation referred to.

Formal changes may be made in the specific embodiment of the invention described without departing from the spirit and substance of the invention, the scope of which is commensurate with the appended claims.

What is claimed is:

1. The combination of a toilet seat having an opening extending inwardly from its forward face, headed members secured to the under side of said seat with their heads spaced from the under surface of said seat, and a pliable rubber cup-shaped shield located in said opening with the concave portion thereof directed inwardly, said shield having horizontally extending portions on opposite sides of said shield with openings extending therethrough, said shield being attached to said seat by buttoning said horizontally extended portions to said headed members.

2. The combination of a toilet seat having an opening extending inwardly from its forward face, members secured to the underside of said seat projecting downwardly therebelow, the projecting portions of said members having enlarged ends in spaced relation to the bottom of said seat, and a pliable rubber cup-shaped shield located in said opening with the concave portion thereof directed inwardly, laterally extending means positioned on opposite sides of said shield providing resilient engagement means, the construction and arrangement of said laterally extending means being such as to resiliently and removably engage the projecting portions of said members.

3. The combination of a toilet seat having an opening extending inwardly from its forward face, members secured to the under side of said

seat projecting downwardly therebelow, the projecting portions of said members having enlarged ends in spaced relation to the bottom of said seat, and a pliable rubber cup-shaped shield located in said opening with the concave portion thereof directed inwardly, said shield having laterally extending portions positioned on opposite sides of said shield providing resilient engagement means, the construction and arrangement of said laterally extending portions being such as to resiliently and removably engage the projecting portions of said members with the upper surfaces of said laterally extending portions bearing against the under surface of said seat.

15 4. The combination of a toilet seat having an

opening extending inwardly from its forward face, members secured to the under side of said seat projecting downwardly therebelow, the projecting portions of said members having enlarged ends in spaced relation to the bottom of said seat, and a pliable rubber cup-shaped shield located in said opening with the concave portion thereof directed inwardly, said shield having laterally extending portions positioned on opposite sides of said shield with openings therethrough, the construction and arrangement of the openings through said laterally extending portions being such as to resiliently and removably engage the projecting portions of said members.
